UNITED STATES PATENT OFFICE.

REUBEN HALEY, OF BEAVER, PENNSYLVANIA, ASSIGNOR TO UNITED STATES GLASS COMPANY, OF PITTSBURGH, PENNSYLVANIA, A CORPORATION OF PENNSYLVANIA.

DESIGN FOR A GLASS VESSEL OR SIMILAR ARTICLE.

48,717.

Specification for Design.

Patented Mar. 14, 1916.

Application filed January 7, 1916. Serial No. 70,879. Term of patent 7 years.

To all whom it may concern:

Be it known that I, REUBEN HALEY, a citizen of the United States, and residing at Beaver, in the county of Beaver and State of Pennsylvania, have invented a certain new, original, and ornamental Design Applied to a Glass Vessel or Similar Article, of which the following is a specification, reference being had to the accompanying drawings, forming a part thereof, wherein—

Figure 1 is a bottom plan view of a glass vessel to which the design is applied, and Fig. 2 is a side elevation of the same.

Copies of this patent may be obtained for five cents each, by addressing the "Commissioner of Patents, Washington, D. C."

The design is shown applied to a dish of conventional form, the shape or outline of which is not claimed.

I claim:

The ornamental design applied to a glass vessel or similar article, substantially as shown.

REUBEN HALEY.
